UNITED STATES PATENT OFFICE.

CLAUDE D. JONES, OF OKLAHOMA, OKLAHOMA.

TOILET-PAPER CUTTER.

1,326,738.

Specification of Letters Patent. Patented Dec. 30, 1919.

Application filed September 3, 1918. Serial No. 252,395.

To all whom it may concern:

Be it known that I, CLAUDE D. JONES, a citizen of the United States, residing at Oklahoma city, in the county of Oklahoma, 5 and State of Oklahoma, have invented certain new and useful Improvements in Toilet-Paper Cutters, of which the following is a specification.

The present invention relates to improvements in toilet paper-cutters, of the feed roll and rotary cutter type, and the machine is designed especially for use in a vending apparatus or coin machine, for dispensing sanitary seat covers for toilet use.

15 In the present invention a feed roll of paper is employed, and by the utilization of a rotary cutter and oscillating knife, sheets of the roll are successively cut and severed from the roll, the feeding of the roll being 20 in the form of a folded strip, so that the rotary cutter may cut a tongue from the sheet before it is severed by the oscillating or pivoted knife.

The invention consists essentially in certain 25 novel combinations and arrangements of the actuating parts of the machine involving the coin mechanism and sheet severing mechanism as will be hereinafter more fully pointed out in the claim.

30 Figure 1 is a side elevation of a complete vending machine embodying the invention.

Fig. 2 is a front elevation of the machine, these two views showing in dotted lines the relative position of parts.

35 Fig. 3 is an enlarged view partly in section showing the actuating mechanism operative in the presence of a coin.

Fig. 4 is a front elevation view of a part 40 of the machine showing the free end of the severing knife and its connections, and a portion of the coin chute and connections.

Fig. 4^a is a detail view in elevation at the pivoted end of the knife.

Fig. 5 is a side view showing the coin 45 lever, and the severing knife and connections operated thereby.

Fig. 6 is a sectional view through the delivery rolls, showing also the severing knife closing the delivery chute.

50 Fig. 7 illustrates the roll of paper on its reel, and a sheet severed therefrom.

Fig. 8 is a plan view of a sheet after having been severed, ready for use.

Fig. 9 is a diagrammatic view showing the tongue cutting rotary knife. 55

The seat cover, as it issues from the machine, is folded, as indicated at 1 Fig. 7, and this sheet has cut therefrom an elliptical tongue 2, to be used for protective purposes, leaving a central opening 3 in the sheet when unfolded, which is cut on line 4, and a neck 5 is provided leaving the tongue attached to the sheet, so that it may be folded down within the seat opening for sanitary purposes. These seat covers are dispensed 60 from the box or housing 6 through the slot 7 in the front thereof by means of the instrumentalities actuated by the crank 8 and the chopping lever 9, the crank located on the outside of the machine, and the lever projecting through the front of the housing in slot 9. 70

Within the housing is arranged and fixed a supporting frame 10 for the operating parts of the device, and within the housing 75 and frame the two rollers 11 and 12 are journaled, and the rollers are held in frictional contact by means of the side springs 14, which connect the two shafts 15 and 16 of the respective rolls. 80

The two rollers are equipped with a rotary cutting device in the form of a circumferentially arranged cutting knife, preferably with a serrated edge, as 17, and the upper roll has a complementary recess 18 to receive this knife or cutter. The special arrangement of the cutting device will be apparent in Figs. 2 and 9 where it will be seen that the front end of the knife or cutter starts at the end of the roller, and the rear 90 end or finish of the cutter is located a short distance from the end of the roll, thus providing for cutting of the tongue 2 without actually severing it from its sheet, by leaving the neck attached to the sheet. The sheet 95 or seat cover is severed from the strip by means of the longitudinally extending pivoted knife blade 19, pivoted at 20 in the frame and co-acting in conjunction with the slotted vertically arranged plate 21 having 100 the delivery slot 22, and extending across the machine in front of the rollers between the frame members to which it is secured. Preferably the knife is shorter than the width of the paper strip as it issues from 105 its rollers, so that the sheet is not severed

entirely from the strip, but is left dangling in front of the machine after having been delivered through the slot 7, and as the cover emerges through the slot it is to be torn off, 5 by hand, when grasped by the operator.

The two fold web or strip is wound upon the spool 23 journaled in the long inclined slots 24 so that the journal ends 25 of the spool may be guided in the slots as the size 10 of the roll decreases, and the roll rests upon the top of the upper roller 11 as a support, the end of the strip being fed downwardly between the two feed rollers 11 and 12, through the delivery rolls 26 and 27, thence 15 through the slot 22 in the plate 21 for action by the knife 19.

The cutting rollers 11 and 12 are actuated from the crank handle 8 on the shaft 15 through the pair of gears 28 and 29 meshing 20 with each other and at the ends of these two rollers, a pawl 30 being employed in connection with gear wheel 29 to prevent reverse movement of the rollers. The gears are held locked by means of a bell crank 25 lever 31, pivoted at 32, and held off center by means of the spring 33, and the pawl 34 secured at the inner side of the short arm of the lever engages the teeth of the gear 28 see Figs. 3 and 4. The cutting rolls are normally held locked by the pawl, and the pawl is unlocked only by the presence of the chute 35 of a check, in the form of a penny 36, which, when moved or forced downwardly by the pin 37 on the chopping lever, engages 30 a slide lever 38, somewhat S shaped and pivoted at 39 on the free end of the bell crank lever 31. Lever 38 is slotted at 40 and a guide pin 41 fixed to a part of the chute 35 permits a limited swing of the slide lever 35 or re-locking lever on the point 39 as a center and of course the slide lever swings bodily with the bell crank lever on its center 32. The pawl 34 is disengaged positively by action of the pin 37 of the chopping 40 lever and the coin in its engagement with the slide lever 38, and the pawl is again made to engage the teeth of gear 28 when the pin 43' on the lower, roller 12 comes around at the end of the cutting stroke of 45 cutter 17, to strike the cam face 42 of this slide lever or cam lever 38, the encounter of the pin and cam face, or course, swinging the bell crank lever over to the left as in Fig. 3, and returning the cam lever 38 to its 50 normal position as seen also in Fig. 3.

The pivoted knife 19 is held in normal position by the spring 33' and it will be seen that the knife closes the delivery chute 22 when in normal position. The cutting stroke 60 of the knife is an upward swing on its pivot 20 under tension of the spring 33', and the knife is moved from normal position to operative position by means of the chopping lever 9 which has a depending arm 43 and 65 roller 44 engaging the cam arm 45 at the end

of the knife blade and extending to the rear at right angles thereto. When the chopping lever is depressed against the tension of its spring 9^a, it swings the knife blade 19 on its pivot 20, the grooved wheel 44 riding 70 up the edge of the cam arm 45, until the lug 46 on arm 45 encounters the upper side of the cam lug 47 on the swinging latch 48, pivoted at 49 and pulled to the left by spring 50 against the projecting pivot pin 75 39 of the cam lever 38. The pivot pin 39 projects through a slot 39', in the frame 10 and the spring 50 normally holds the latch against this pin, but as the lug 46 rides down on the cam face 51 of the lug 47, the latch 80 is swung to the right in Fig. 5 to permit the lug 46 to pass, when the spring 50 immediately retracts the latch 48 so that the cam lug 47 holds down the cam arm 45 by engagement with the lug 46 thereon. After 85 the knife is held down to its operative position, the spring 9^a retracts the chopping lever 9 to position in Fig. 5 leaving the knife in the dotted position shown. The crank arm 8 is then turned, and after the 90 end of the cutting stroke of the rotating rollers, the lug 43' encounters the cam face 42 of the cam lever, lifting the lever and with it its pin 39, which encounters the cam shoulder 52 of the latch 48 and swings the 95 latch to the right in Fig. 5. Thereupon the two lugs 46 and 47 are disengaged and the knife is swung upwardly on its pivot 20 by its spring 33'. Thus, the first action after placing the penny in the chute or slot is to 100 depress the chopping or operating lever 9 which action simultaneously disengages the pawl 34 from the gear 28 and moves the knife 19 to operative position, after which the chopping lever is permitted to return to 105 normal position by means of its spring 9^a. After the parts are in position as described, the crank handle 8 is given a complete turn from the horizontal position indicated in Figs. 1 and 5, and the desired length of strip 110 is pulled from the roll by the two rollers 11 and 12, the tongue is cut out of the strip and the strip is passed through the delivery chute 22 by means of a pair of delivery rollers 26 and 27, journaled in brackets of the plate 21 and extending across the front of the machine, back of the knife 19. These rollers are positively actuated from the upper roll 11 which has a gear wheel 55 at one end engaging the train of gears 56, 57, and 58 115 (Figs. 5 and 6) to drive the rollers, as well understood, and after the required length of strip, with its cut tongue, has passed through the delivery slot 7, the latch 48 is freed as described, permitting the knife 19 120 to swing upwardly on its operative stroke, severing all but the right end of the strip (see Fig. 4). The strip is left dangling by the uncut portion, and is then torn off by the operator in well known manner. 125 130

Claim:

The combination with a rotary cutting device including a pair of feed rollers with engaging gear wheels, of a locking device 5 therefor comprising a bell crank lever and a spring for holding it off center, a cam lever pivoted on the bell crank lever and a pawl fixed on the bell crank lever to engage

one of the gear wheels, mechanism operative in the presence of a coin for actuating the 10 cam lever to move the bell crank lever for disengaging the pawl, and means on one of the rollers for actuating the cam lever to return the pawl to locked position.

In testimony whereof I affix my signature. 15

CLAUDE D. JONES.
